UNITED STATES PATENT OFFICE.

CHARLES HIATT AND RESCUE B. PAGE, OF LOS ANGELES, CALIFORNIA.

SASH-HOLDER.

950,697.

Specification of Letters Patent.

Patented Mar. 1, 1910.

Application filed December 28, 1908. Serial No. 469,536.

To all whom it may concern:

Be it known that we, CHARLES HIATT and RESCUE B. PAGE, both citizens of the United States, residing at Los Angeles, in the county 5 of Los Angeles and State of California, have invented new and useful Improvements in Sash-Holders, of which the following is a specification.

The objects of our invention are to provide a handy, reliable and inexpensive means 10 to hold the window-sash in any desired position in the window-frame, and to dispense with the sash weight, pulleys and cords used in the ordinary construction, and our invention 15 is particularly adapted for use in inexpensively constructed buildings, such as portable houses, bungalows and the like where the walls are constructed of a single thickness of material.

20 We accomplish these objects by means of the device described herein and shown in the accompanying drawings, in which:—

Figure 1—is a front elevation of a window-sash in place in a window-frame with 25 our improvement placed therein, the casing of the window-frame being broken away to show our improved sash holder in place in the window-frame. Fig. 2—is a section taken on line 2—2 of Fig. 1 looking in the direction indicated by the arrow head thereon. Fig. 3—is a front elevation of a fragment of 30 a window-frame and sash showing the knob projecting from the sash holder.

In the drawings, 1 represents the window-frame in which the upper sash 2 is 35 fixed, the lower sash being slidably mounted in the frame. Disposed to the right of the lower sash and having a limited vertical movement therein, is the sash holder 4. This 40 sash holder is wedge-shaped in general outline, the butt of the same being on top and the arrow point thereof at the bottom. The window-frame is provided with an inclined bearing face 5 adapted to contact with and 45 engage one side of the wedge-shaped holder, and when the holder is in its depressed position it will contact one side with the window-sash which is inclined to the vertical as clearly shown in Fig. 1, and the other side 50 with the inclined frame and hold the sash

against any movement in the frame. The sash holder is kept in its depressed or normal position by its weight and it may be weighted for that purpose and will while depressed always hold the sash tightly in the frame. 55

We have shown a coiled spring 6, its lower end resting upon the upper end of the sash holder and its upper end in place and resting against the window-frame. This is a mere modification which will seldom if ever be 60 required. In Fig. 1 the lower sash is shown partly raised and held tightly in this position by the downward impulse of the sash holder caused by its own weight. Now when it is desired to move the sash up or down the 65 knob 7 which projects outwardly from the sash holder (the shank 8 of which projects through the longitudinal slot 9 in the window-frame) is raised up, this will carry the sash holder upwardly out of its locked 70 engagement between the sash and the frame and permit the movement of the sash up or down as desired. Upon releasing the knob the wedge-shaped sash stopper will immediately drop and lock the sash and frame 75 together and prevent any further movement of the sash.

Having described our invention what we claim as new and desire to secure by Letters Patent is:—

80 A sash-holder, comprising a wedge-shaped member, said member being disposed between one of the vertical edges of the sash and its guideway formed in the window frame, both the vertical edge of the sash and 85 its guideway being inclined in the same general direction but at different angles to each other, the wedge-shaped member being inclined on its vertical contacting edges to correspond with the inclines formed on the 90 sash and its guideway.

In witness that we claim the foregoing we hereunto subscribed our names this 21st day of December, 1908.

CHAS. HIATT.
R. B. PAGE.
